Primary Examiner — Khawaja Anwar*Assistant Examiner* — Taylor O Mortorff(74) *Attorney, Agent, or Firm* — MUNCY, GEISSLER, OLDS & LOWE, P.C.(57) **CLAIM**

The ornamental design for a scraper cover as shown and described.

DESCRIPTION

FIG. 1 is a perspective view of a scraper cover showing my new design;

FIG. 2 is another perspective view thereof;

FIG. 3 is a left view thereof;

FIG. 4 is a top view thereof;

FIG. 5 is a bottom view thereof;

FIG. 6 is a rear view thereof; and,

FIG. 7 is cross-sectional view thereof.

The broken lines depict portions of the scraper cover that form no part of the claimed design. The dash-dot lines illustrate the location form which the section drawings are created and shown in FIGS. 6 and 7. The dash-dot lines form no part of the claimed design.

1 Claim, 7 Drawing Sheets(56)
